UNITED STATES PATENT OFFICE.

JAMES A. GRAY, OF NEW YORK, N. Y.

TRAIN-STOPPING APPARATUS.

1,142,697.

Specification of Letters Patent. Patented June 3, 1915.

Application filed October 3, 1914. Serial No. 864,837.

To all whom it may concern:

Be it known that I, JAMES A. GRAY, a citizen of the United States of America, residing at New York, in the county of New York and State of New York, have invented new and useful Improvements in Train-Stopping Apparatus, of which the following is a specification.

This invention relates to improvements in train stopping apparatus and is in the nature of an improvement upon my previous Patent No. 1,117,034.

In carrying out the present invention, it is my purpose to provide train stopping apparatus which will be speed controlled and whereby the propelling power of the motor car will be cut off and the brakes applied in the event of the car or train running by a danger signal above a predetermined speed and whereby the propelling power of the car and the brake mechanism will be uninfluenced when the train is traveling below the prescribed speed limit so that the train may run into an occupied block with caution.

With the above and other objects in view, the invention consists in the construction, combination and arrangement of parts hereinafter set forth in and falling within the scope of the appended claims.

In the accompanying drawing; Figure 1 is a view in elevation of a locomotive equipped with the present invention. Fig. 2 is a view in side elevation of the drums and gear wheel illustrated in Fig. 1. Fig. 3 is a sectional view showing a detail of the invention.

Referring now to the drawing in detail, A designates the cab end of the boiler of a steam driven locomotive. Journaled in suitable horizontally alining bearings carried by a bed plate 56' bolted to the head of the boiler within the engine cab is a shaft 55' and keyed upon the shaft 55' is a gear wheel 57' carrying upon one side a large drum 58' and a relatively small drum 59, while also mounted upon the shaft 55' is a loose pulley 60 and a fast pulley 61. Trained over the loose pulley and adapted to be thrown from the latter onto the fast pulley is a belt 62 adapted to be driven from a pulley 70 fast upon a countershaft 71 journaled in horizontally alining bearings and equipped with a sprocket wheel 72 over which and a sprocket wheel keyed upon one of the axles of the locomotive is trained an

endless chain 73 whereby motion is imparted to the countershaft 71. In this instance, the belt shipper lever indicated at 32 is connected through the medium of a wire or other flexible element 63 with a tripping device carried by the locomotive and under the control of the railroad signals. The gear wheel 57' meshes with the teeth of a rack bar 74 secured to the under side of a throttle valve rod, while a chain 64 or other flexible element has one end connected to and trained about the relatively large drum 58', such chain leading to and is connected with a valve located in the train line air pipe and adapted, when opened, to bring about, in effect, a service application of the brakes, in contra-distinction to an emergency application. A second chain 66 or other flexible element has one terminal thereof connected to the drum 59 and is wrapped thereabout and has the free end thereof connected to the engineer's brake valve so as to effect an emergency application of the brakes to the wheels. Thus, it will be seen that under all circumstances, the brakes will be applied in such manner as to reduce the wear and tear on the rolling stock incident to a sudden emergency application.

The above described mechanism is clearly illustrated in my allowed application and forms no part of the present invention, but has been described merely to show the application of the present invention.

As previously stated, the shipper rod 32 is adapted to be actuated from a tripping device under the control of the road signals and in accordance with the present invention the rod is held against movement to ship the belt from the loose pulley to the fast pulley, while the train is traveling below a certain speed and is relieved of the influence of such holding means when the train is running above the prescribed speed. In the present instance, this speed controlled mechanism comprises a vertical shaft 75 connected with one of the axles of the locomotive through suitable gearing and adapted to be rotated therefrom in the movement of the car. Fixed to the upper end of the shaft 75 is a collar 76 and pivoted to the collar 76 at diametrically opposite points are arms 77 having the outer ends thereof equipped with weighted balls 78 adapted to fly outwardly under the action of centrifugal force under the action of the shaft 75.

2

Slidably mounted upon the shaft 75 below the fixed collar 76 is a collar 79 connected through the medium of links 80 with the arms 77 respectively. Connected with the collar 79 and depending therefrom is an arm 81 having the lower end thereof normally engaging a lug 82 on the shipper rod 32. As long as the locomotive is running below the predetermined speed, say, for instance, ten miles per hour, the lower end of the arm 81 remains in engagement with the lug 82, thereby holding the shipper rod 32 against movement under the action of the tripping device when the latter is operated from the signal blade. When, however, the train exceeds the prescribed speed, the balls 78 fly outwardly under the action of centrifugal force and so elevate the collar 79, thereby drawing the lower end of the arm 81 out of engagement with the lug 82 and permitting the shipper rod to operate when the tripping device is actuated. In the present instance, the upper edge of the lug end of the shipper rod 32 is beveled as clearly illustrated in Fig. 3 so that when the shipper rod is restored to normal position, succeeding the release of such rod by the governor controlled arm 81, the arm 81 will be elevated in order to freely pass the lug 82 and drop behind the latter. In this form of my invention, I have shown the coacting ends of the arm 81 and shipper rod 32 as slidably mounted within a block having right angular arranged bores for the reception of such ends, as clearly illustrated in Fig. 3 of the drawing.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

1. In train stopping apparatus, the combination with a shaft adapted for rotary movement, connections between said shaft and the throttle valve and engineer's brake valve whereby the throttle valve will be closed and the brake valve actuated to effect an application of the brakes when the shaft is rotated, fast and loose pulleys on said shaft, a belt trained over said pulleys, a shipper rod for shifting the belt from the loose pulley to the fast pulley to rotate

the shaft, and speed controlled means holding said shipper rod against movement while the train is traveling below a predetermined speed. 60

2. In train stopping apparatus, the combination with a shaft adapted for rotary movement, connections between said shaft and the throttle valve and engineer's brake valve whereby the throttle valve will be closed and the brake valve actuated to effect an application of the brakes when the shaft is rotated, fast and loose pulleys on said shaft, a belt trained over said pulleys, 70 a shipper rod for shifting the belt from the loose pulley to the fast pulley to rotate the shaft, a lug on said shipper rod, an arm normally engaging said lug and holding the shipper rod against movement, and speed 75 controlled means for relieving said lug of the influence of said arm when the train is traveling above a prescribed speed.

3. In train stopping apparatus, the combination with a shaft adapted for rotary movement, connections between said shaft and the throttle valve and engineer's brake valve whereby the throttle valve will be closed and the brake valve actuated to effect an application of the brakes when the shaft 80 is rotated, fast and loose pulleys on said shaft, a belt trained over said pulleys, a shipper rod for shifting the belt from the loose pulley to the fast pulley to rotate the shaft, a lug on said shipper rod, an arm 85 normally engaging said lug and holding the shipper rod against movement, and means responsive to the action of centrifugal force to relieve said lug of the influence of said arm when the train is traveling above a pre- 90 determined speed. 95

4. In train stopping apparatus, the combination with a shaft adapted for rotary movement, connections between said shaft and a controlling element of the motor car, 100 fast and loose pulleys on said shaft, a belt trained over said pulleys, a shipper rod for shifting the rod from the loose pulley to the fast pulley to rotate the shaft, and speed controlled means holding said shipper rod 105 against movement while the train is traveling below a predetermined speed.

In testimony whereof I affix my signature in presence of two witnesses.

JAMES A. GRAY.
